CLAIM

The ornamental design for an "educational projector device" as shown and described.

DESCRIPTION

FIG. 1 is a perspective view of an educational projector device showing my new design;

device, showing my new design;
FIG. 2 is a front elevational view thereof;
FIG. 3 is a rear elevational view thereof;
FIG. 4 is a left side elevational view thereof
FIG. 5 is a right side elevational view thereof;
FIG. 6 is a top plan view thereof; and,
FIG. 7 is a bottom plan view thereof.

The broken line showing of eight words formed in a cap of the device are included for the purpose of illustrating environmental structure and forms no part of the claimed design.

1 Claim, 2 Drawing Sheets
